UNITED STATES PATENT OFFICE

152,018

DESIGN FOR A STOCKING

Benjamin Franklin Playford, Cape May, N. J.

Application March 24, 1948, Serial No. 145,326

Term of patent 14 years

(Cl. D47—7)

To all whom it may concern:

Be it known that I, Benjamin Franklin Playford, a citizen of the United States, residing in Cape May, in the county of Cape May and State of New Jersey, have invented a new, original, and ornamental Design for a Stocking, of which the following is a specification, reference being had to the accompanying drawing, forming a part thereof.

The figure in the drawing is a side elevation of a stocking embodying my new design, the latter being characterized by a leg portion of a solid color, a heel and foot portion of the same color but deeper in shade, and a substantially linear boundary of distinctive color contrasting with both said portions between the leg portion and that part of the heel and foot portion which is visible above the shoe counter when the stocking is being worn with a shoe, conventional shading

and hatching being employed to illustrate the location of the several distinctive shade and color areas without, however, showing in detail any individual stitches of the fabric.

I claim:

The ornamental design for a stocking, substantially as shown and described.

BENJAMIN FRANKLIN PLAYFORD.
